HIGH EFFICIENCY TRAVELING WAVE TUBES
 Arie L. Eichenbaum, Princeton, N.J., assignor to Radio
 Corporation of America, a corporation of Delaware
 Filed July 30, 1958, Ser. No. 752,120
 14 Claims. (Cl. 315—3.5)

This invention relates to high efficiency traveling wave tubes and particularly to means for maintaining the average velocity of the electron beam thereof substantially constant throughout its traversal of the slow wave propagating structure.

In one form of a conventional traveling wave tube a helical, slow wave-propagating structure is provided between an electron gun and an electron collector. An RF signal is fed to the helix at one end and an amplified output of the input signal is taken from the other end of the helix. The electron beam, which is focused to pass axially along and inside of the helix, is modulated by interaction with the RF wave on the helix during its traversal of a first portion of the helix and then in turn gives up energy to effect an amplification of the wave.

The phase velocity of an RF wave along a traveling wave tube helix of uniform diameter and pitch is constant. In order to obtain optimum operation so as to achieve the highest possible gain, it is necessary that the average velocity of the electron beam be maintained nearly equal to the phase velocity of the RF wave traveling along the helix. However, in giving up its own axial kinetic energy in order to produce amplification, the electron beam is slowed down. This slowing down of the electron beam increases exponentially along that portion of the helix where amplification is effected. Eventually the beam velocity becomes so much below the phase velocity of the traveling wave that amplifying interaction between the wave and the beam is impossible, and no further amplification of the wave is produced. Such a condition places a limitation upon the amplification, or gain, of the tube. R. W. Peter proposed in U.S. Patent No. 2,817,037, issued December 17, 1957, that the D.C. space potential along the electron beam of a traveling wave tube could be varied by providing a series of helices and connecting them to increasing D.C. potentials. By so doing energy can be supplied to the electron beam so as to maintain its average velocity constant.

An object of this invention is to provide a novel and improved arrangement for maintaining a constant average beam velocity in a traveling wave tube by providing one or more D.C. potential establishing electrode elements along and adjacent the helix so as to produce an increasing beam potential therewith.

Briefly, according to my invention, a non-propagating D.C. potential establishing electrode means is disposed adjacent the helix or other slow wave propagating structure with a constant phase velocity in a traveling wave tube and may, for example, comprise a plurality of rings or cylinders disposed around and along the helix and connected to successively increasing D.C. potentials. The accelerating axial electrostatic fields produced by the potentials on the rings penetrate to within the helix where they establish an increasing beam potential gradient therewith. Such increasing potential gradient serves to maintain the beam velocity constant notwithstanding the fact that the beam is giving up energy to the RF wave in order to produce amplification thereof. Alternatively, the D.C. potential establishing electrode means may comprise a single ring in the form of a hollow frusto-conical member surrounding and extending along at least the final portion of the helix with its smaller diameter end adjacent the electron collector end of the helix. A single D.C. potential, higher than the helix potential, connected to the

2

member serves to provide an increasing beam potential gradient within and along the helix.

In the drawings:

FIG. 1 is an axial section view of a helix type traveling wave tube and circuit embodying one form of my invention; and

FIGS. 2, 3, 4, 5, 6, and 7 are partly schematic axial section views of other embodiments of my invention.

FIG. 1 shows a helix type traveling wave tube 10 comprising a dielectric envelope 12 containing an electron gun 14 at one end and an electron collector 16 at the other. A slow wave propagating helical conductor or helix 18 of uniform diameter and pitch is disposed between the electron gun 14 and the electron collector 16 and is axially aligned therewith. The helix 18 is supported on three dielectric rods 20, two of which are shown in FIG. 1, and a series of dielectric rings 22 which are notched to receive the rods 20. One end of the helix 18 is provided with an axial extension 24 to couple with an RF signal supplied by an input wave guide 26. The other end of the helix 18 is similarly provided with an extension 28 to couple an amplified wave produced on the helix to an output wave guide structure 30.

According to my invention, a plurality of conductive rings 32 are disposed around and uniformly spaced along the helix 18. The rings 32 are connected to a voltage divider 34 which in turn is connected to two taps on a D.C. voltage source 36. Predetermined, desired voltages are also supplied by the voltage source 36 to the electron gun 14, the helix 18, and the electron collector 16. Means, such as an elongated electromagnet surrounding the envelope, (not shown) is provided for producing an axial magnetic field B as illustrated by the arrow.

The electron gun 14 is conventional and comprises a cathode 38, heater 39, focusing or shield electrode 40, first anode 42 and second anode 43. In operation of the tube 10 according to my invention, electrons are emitted by the cathode 38 and are focused and accelerated by the shield electrode 40 and anode 42, respectively, into a beam of electrons which travel along the tube axially through the helix 18 where they are collected by the collector 16. According to the principle of operation of the conventional traveling wave tube, an RF input signal is fed through the input wave guide 26 and coupled to the extension 24 of the helix 18 from whence it is propagated along the helix at a constant phase velocity substantially less than the velocity of light and coupled from the extension 28 at the other end to the output wave guide 30. The initial beam velocity is adjusted, by varying the D.C. potential of the helix, to a value substantially equal to the phase velocity of the traveling wave on the helix. The RF signal coupled to the helix serves to velocity modulate the beam during its traversal of the first portion of the helix. During its traversal of the remainder of the helix the velocity modulated beam gives up energy to the traveling RF wave to produce an amplification of the wave. To prevent a decrease of average axial beam velocity due to the energy given up thereby to the traveling wave, progressively increasing D.C. potentials are connected to the rings 32 to produce an accelerating axial electric field. Since in the absence of the rings 32 as provided by my invention the beam velocity would fall off in an exponential manner, the D.C. potentials connected to the rings 32 are preferably of exponentially increasing values so as to properly compensate for the energy lost by the beam. For example, 2400 volts D.C. may be connected to the second anode 43 and helix 18 and 1800 and 3000 volts to the ends of the voltage divider 34. The 1200 voltage drop across the voltage divider 34 is divided into 8 increments as illustrated in FIG. 1 so as to give the desired exponential increase to the beam potentials along the helix. In the

arrangement as illustrated in FIG. 1, the helix potential of 2400 volts may be connected to the collector 16, 2000 volts to the anode 42, and 0 or ground to the cathode and shield 38 and 40.

It should be noted that the D.C. potential range applied to the series of rings 32 in the illustrative embodiment of FIG. 1 is given as 1800-3000 volts only by way of example. Actually the potentials applied to the rings 32 may extend over a wider or narrower range or may be higher or lower relative to the helix potential depending upon other tube parameters. In the illustrative embodiment of FIG. 1 the helix potential lies intermediate the extremes of the potentials applied to the rings 32. This condition serves to minimize potential difference between any one ring 32 and the helix, and as such, minimizes the danger of arcing therebetween. It will be appreciated that according to my invention the helix potential could be such as to fall outside the range of potentials applied to the rings 32.

According to my invention the D.C. potentials applied to the rings 32 provide electrostatic fields thereabout. These electrostatic fields penetrate into the interior of the helix 18 where they influence the velocity of the electron beam. Inasmuch as the helix 18 is interposed between the rings 32 and electron beam, the field effect of the rings 32 is only partially felt by the beam. The influence of the fields of the rings 32 upon the beam may be calculated according to known principles of field penetration through a grid structure. In the embodiment as illustrated in FIG. 1 this penetration might be in the order of $\frac{1}{6}$ of the voltage difference between the potential on rings 32 and on the helix 18. For example, the ring 32a, which has a potential of 3000 volts applied thereto, might provide an effective beam accelerating potential inside the helix 18 opposite the ring 32a of approximately 2520 volts, i.e., $[2400 + \frac{1}{6} (3000 - 2400)]$.

In the embodiment illustrated in FIG. 1, nine rings 32 are used. Theoretically, there is no upper limit to the number of rings which can be used. The more rings used the smoother the transition of the beam potential along the helix. However, experience has shown that the use of from approximately three to six rings in practicing my invention is preferred for practical considerations.

Although the optimum arrangement is to provide an exponentially increasing D.C. potential along the helix as illustrated by FIG. 1, it will be appreciated that such is not an essential requirement to the practice of my invention. The uniformly spaced rings 32 of the tube 10 could be connected to uniformly increasing D.C. potentials. However, since in the absence of the rings 32 the average beam velocity would drop off exponentially, optimum correction involves application of an exponentially increasing D.C. potential along the helix. One way of providing such an exponentially increasing potential is as illustrated in FIG. 1 wherein the potential bearing rings 32 are uniformly spaced with exponentially increasing potentials being connected thereto. Alternatively, an exponentially increasing potential along the helix can be obtained by providing exponentially positioned rings along the helix with uniformly increasing potentials connected thereto. When the latter arrangement is used, successive rings should be of exponentially decreasing length according to their exponential positioning in order to produce the smoothest possible transition of D.C. potential along the helix. FIG. 2 illustrates such an alternative.

FIGS. 2 through 7 illustrate other embodiments of the invention. In these figures, the envelope 12, input and output wave guides 26 and 30, heater 39, shield electrode 40 and first anode 42 of FIG. 1 are not shown, to simplify the drawing.

In FIG. 2 there is schematically shown a series of rings 44 disposed around and along a helix 18. The rings 44 are connected to a series of taps on a voltage divider 46 so as to supply uniformly increasing potentials to successive rings along the helix 18. A voltage source 48 may,

for example, be tapped to supply 2400 volts to the helix 18 and some range of potentials, e.g., 1800 and 3000 volts respectively to the ends of the voltage divider 46. In order to obtain the desired increasing beam potential gradient along the helix 18, the rings 44 are made of different lengths and are disposed so that the longer ring 44a is adjacent the electron gun and of the helix 18, and that successive rings in the direction toward the collector end of the helix are of successively shorter lengths. The rings 44 are decreased in length in an approximately exponential manner so as to approximate the desired exponential increase of the beam-influencing potential along the helix 18. In the schematic illustration of FIG. 2, a series of 6 rings 44 are shown. It will, however, be appreciated that more or fewer rings can be used in accordance with the teaching of my invention.

In an actual tube made according to the teaching of FIG. 2, three rings 44 were provided having lengths of 3.5, 0.5, and 0.25 inches. The helix of the tube was connected to a D.C. potential of 800 volts and the three rings 44 to potentials of 700, 900, and 1100 volts respectively. A substantial improvement of synchronism between the average beam velocity and the traveling wave phase velocity was noted.

FIG. 3 schematically illustrates an arrangement wherein a plurality of rings 50-59, all of the same size, are disposed around and along a helix 18. The embodiment of FIG. 3 differs from that of FIG. 1 in that periodic electrostatic focusing of the electron beam is provided in combination with an increasing beam-influencing potential. The alternate even numbered rings 50, 52, 54, 56, and 58 are supplied with increasing D.C. potentials by connection to a series of taps on a first voltage divider 62. The alternate odd numbered rings 51, 53, 55, 57, and 59 are also supplied with increasing, but considerably lower, D.C. potentials by connection to a series of taps on a second voltage divider 64. The first voltage divider 62 may, for example, be connected to a voltage source 66 to 2000 and 2800 volt taps and the second voltage divider 64 to the voltage source 66 to 400 and 1200 volt taps. The helix 18 may, for example, be connected to the 1200 volt tap on the voltage source 66. Thus, the rings serve to provide an increasing beam-influencing potential along the helix 18, and any two adjacent rings, i.e., 52 and 53, being at substantially different potentials, serve to provide periodic electrostatic focusing of the electron beam. In accordance with the previously discussed teaching of optimum correction, the potentials supplied to either series of alternate rings may be made of an exponentially increasing nature.

FIG. 4 illustrates a modification of the arrangement of FIG. 1, wherein a series of rings 70 are disposed around and along a helix 18 and are connected to exponentially increasing D.C. potentials, but are elongated and lapped over each other. Each ring 70 is made up of a first tubular section 72 of one diameter and a second tubular section 74 of a greater diameter. The diameters of the two tubular sections are so relatively dimensioned that the greater diameter section of one ring can be telescoped over the smaller diameter section of an adjacent ring. By so overlapping the rings 70, an RF shield is provided around the helix 18. Moreover, the rings 70 can be so dimensioned that in overlapping with an adjacent ring, open quarter wave lines can be approximated by the space 76 between the rings. Thus, the series of overlapped rings appears as a continuous RF shield along the length of the helix 18 and as such prevents leakage of RF energy from the helix. Such overlapping also serves to provide a smooth transition of D.C. beam potential increase from ring to ring along the helix 18.

It will, of course, be appreciated that the teaching of uniformly increasing potentials applied to exponentially decreasing sized rings, as illustrated in FIG. 2, can be incorporated with the overlapping feature of FIG. 4. Likewise, the combined features of periodic electrostatic focus-

ing and increasing beam potentials gradient along the helix as illustrated in FIG. 3 can be combined with the overlapping teaching as illustrated in FIG. 4.

FIG. 5 schematically illustrates still another embodiment of my invention wherein a hollow electron beam is projected along and inside the helix 18 by means including an annular cathode 80. An increasing beam potential gradient along the helix 18 according to my invention is established by a resistive rod 82 extending coaxially within and along the helix 18. The resistive rod 82 is so sized that it permits the hollow electron beam to pass along the helix, surrounding but out of contact with the rod 82.

In order to provide the desired increasing beam potential gradient along the helix 18, the extreme ends of the resistive rod 82 are connected to a pair of taps on a voltage source 84. For example, the helix may be connected to a 2500 volt tap with 2000 and 3000 volts, respectively, being connected to the ends of rods 82. In order to provide an exponentially increasing beam potential gradient, the resistance of the rod 82 may be variable along its length. This may be provided either by tapering the rod or making the rod of uniform diameter but of an increasing resistive material throughout its axial extent.

FIGS. 6 and 7 illustrate preferred embodiments of my invention which have an advantage over the embodiments of FIGS. 1-5 in that only one extra D.C. voltage, and hence tube lead-in, is necessitated for practicing the invention. In the embodiment of FIG. 6 the electrode means for effecting a progressively increasing beam potential gradient along the helix comprises a single member in the form of a hollow frusto-conical member 90. The member 90 is disposed around and along the helix 18 with its larger diameter end adjacent the electron gun end of the helix. A single D.C. potential is applied to the member 90 by a D.C. voltage source 92, which also supplies a somewhat lower potential to the helix 18.

The unipotential frusto-conical member 90 serves to provide an increasing beam potential gradient along and within the helix 18 by virtue of its progressively closer spacing thereto along the helix 18. It can be shown mathematically that the effective potential existing along and within the helix as modified by the member 90 is a logarithmic function of the radial spacing of the member 90 from the helix 18. The greater the spacing, the less is the penetration of the potential of the member 90 to within the helix. Such logarithmic function, being itself of an exponential nature, serves to provide the compensation of an exponentially increasing beam potential gradient required for optimum correction. The desired compensation can therefore be provided by use of a conically tapered member, as illustrated. This logarithmic function can be mathematically approximated by well known equations used to express amplification in a triode as determined by a particular grid configuration. Reference is made to § 7.7 of Vacuum Tubes by Karl R. Spangenberg for mathematical expressions defining such effective penetration.

FIG. 7 illustrates the novel portion of an actual traveling wave tube, constructed according to the teaching of FIG. 6, incorporating a hollow frusto-conical section 92 surrounding the helix 18 and extending approximately only the last $\frac{1}{6}$ the length thereof. The approximate $\frac{5}{6}$ remaining length of the helix adjacent the electron gun end of the tube was surrounded with a straight hollow cylinder 94 joined to the large diameter end of the frusto-conical section 92. It will be appreciated that such a composite cylindrical-conical structure, although not providing the ultimate in exponential compensation, will provide exponential compensation over the final $\frac{1}{6}$ portion of the helix where velocity fall-off of the electron beam is most pronounced. Hence, use of a straight cylinder 94 for the first $\frac{5}{6}$ length of the helix permits the use of a much smaller diameter vacuum envelope than is required by the frusto-conical member 90 of FIG. 6.

In the tube of FIG. 7, incorporating the composite

cylindrical-conical structure, a helix 18 having a mean diameter of 0.250 inch was provided. The axial length of the frusto-conical section 92 of the composite structure was approximately 2.2 inches and had an I.D. at the small end thereof of 0.275 inch and an I.D. at the larger end thereof of 0.400 inch. The cylindrical portion 94 of the composite structure, connected to the large end of the frusto-conical portion 92, extended for a distance of approximately 8 inches toward the electron gun of the tube. The I.D. of the cylinder 94 portion was 0.400 inch, the same as that of the larger end of the frusto-conical portion 92. The tube was operated with a D.C. potential of 4800 volts on the helix 18, and 5400 volts on the composite cylindrical-conical structure 92-94. For all practical purposes the average velocity of the electron beam was measured to be effectively constant and in synchronism of the phase velocity of the traveling wave throughout the helix of the tube.

Several advantages are realized from a practice of my invention. Foremost of these is the increased overall efficiency of the tube. Since, according to my invention, substantial synchronism of beam and phase velocity is maintained, greater amplification of the traveling RF wave is obtained. And, since overall tube efficiency is equal to RF power out divided by D.C. power in, an increased efficiency follows.

A second advantage resides in the improved linearity of amplification at high power levels. This is apparent since amplification falls off as the beam and phase velocities fall out of synchronism. And since extraction of energy, or power, from the beam causes a loss of synchronism, and since such energy extraction is greatest at high power levels, it follows that linearity of amplification must necessarily suffer with high power amplification in the absence of compensation for the slowing down of the beam.

A third advantage results from auxiliary beam focusing obtained by virtue of the helix being immersed in an electro-static field more positive than that provided by the helix potential itself. Due to this immersing field supplied by the adjacent electrode means according to my invention, an electron within the helix exists in a field more positive than the potential of the helix. Hence, a force is exerted on the electron tending to urge it toward the center of the helix.

In event that an electron does have sufficient transverse velocity to enable it to travel toward the helix plane, it will immediately be subjected to the more positive field of the surrounding rings and be attracted thereto on through and away from the helix. Such a condition serves to greatly minimize helix interception of electrons.

It will also be appreciated that in accordance with the embodiment of FIG. 3, my invention can provide periodic electro-static focusing without the necessity of additional structure. Hence, maintenance of constant average beam velocity and periodic focusing can be conveniently combined.

An additional, and very important, advantage of the preferred embodiment of my invention illustrated in FIG. 6 is the fact that only a single extra D.C. voltage, and hence tube lead-in, is necessitated in order to provide corrective beam velocity compensation. Such, of course, is made possible by virtue of the use of the single potential-bearing frusto-conical member 90.

What is claimed is:

1. A traveling wave tube comprising an electron gun and an electron collector defining an electron beam path therebetween, a slow wave propagating structure disposed along and continuously coupled to said path, said structure comprising means for propagating waves therealong at a constant phase velocity, and means comprising at least one electrode disposed in spaced relation to and along at least the final portion of said structure for establishing an accelerating electrostatic field in the direction of electron travel.

2. A traveling wave tube according to claim 1, wherein in said electrode is located on the opposite side of said wave propagating structure from said beam path.

3. A traveling wave tube comprising an electron gun and an electron collector defining an electron beam path therebetween, a slow wave propagating structure disposed along and continuously coupled to said path, said structure comprising means for propagating waves therealong at a constant phase velocity, and means comprising at least one electrode disposed in spaced relation to and along at least the final portion of said structure for establishing an accelerating electrostatic field in the direction of electron travel, said means comprising an electrode spaced at decreasing distances transversely from said structure along at least said final portion thereof in the direction of electron travel, and means applying a D.C. potential to said electrode somewhat higher than the potential applied to said wave propagating structure.

4. The traveling wave tube according to claim 1, wherein in said electron gun is annular to provide an electron beam along a hollow beam path and wherein said means comprises a resistive rod coaxially disposed relative to and within said hollow beam path, and means connected to the ends of said rod for establishing an increasing voltage gradient therealong in said direction.

5. A traveling wave tube according to claim 4, wherein in said resistive rod has a variable resistance per unit length increasing in the direction of electron travel.

6. A traveling wave tube comprising an electron gun and an electron collector defining an electron beam path therebetween, a helix of uniform diameter and pitch coaxially disposed relative to and surrounding said electron beam path, and means comprising at least one electrode disposed in spaced relation to and along at least the final portion of said helix for establishing a progressively increasing accelerating electrostatic field in the direction of electron travel along said portion.

7. A traveling wave tube comprising an electron gun and an electron collector defining an electron beam path therebetween, a helix of uniform diameter and pitch coaxially disposed relative to and surrounding said electron beam path, and means comprising at least one electrode disposed in spaced relation to and along at least the final portion of said helix for establishing a progressively increasing accelerating electrostatic field in the direction of electron travel along said portion, said means comprising an elongated hollow member coaxially surrounding said helix and having an inside wall convergently tapered along at least said final portion of said helix in the direction toward said electron collector, and means applying a D.C. potential to said member somewhat higher than the potential applied to said wave propagating structure.

8. A traveling wave tube according to claim 7, wherein said hollow member comprises a hollow cylindrical portion of given inner diameter surrounding about the first

four-fifths of the length of said helix, and a hollow frustoconical portion surrounding the remainder of said helix with a larger diameter end of said frusto-conical portion joined to said cylindrical portion.

5 9. A traveling wave tube comprising an electron gun and an electron collector defining an electron beam path therebetween, a helix of uniform diameter and pitch disposed along and continuously coupled to said electron beam path, and means including a plurality of rings disposed around and along said helix in spaced relation

10 thereto for establishing a progressively increasing accelerating electrostatic field in the direction of electron travel along said helix.

10 15. The traveling wave tube according to claim 9 wherein alternate ones of said rings are connected to predetermined D.C. potentials higher than the D.C. potentials connected to the two rings adjacent any one of said alternate rings.

11. A traveling wave tube according to claim 9 wherein 20 in the midpoints of said rings are progressively closer spaced to each other along said helix in the direction toward said electron collector.

12. The traveling wave tube according to claim 11 wherein 25 said rings along said helix are of progressively shorter length corresponding to the progressively closer spacing of said rings and wherein each ring extends along said helix to within proximity of its adjacent ring.

13. The traveling wave tube according to claim 9 wherein 30 at least some of said rings comprise hollow cylinders each having a first axial section of a given inside diameter and a second axial section of an outside diameter less than said given diameter, said rings being overlapped with a portion of the first section of one ring surrounding a portion of the second section of an adjacent ring.

14. The traveling wave tube according to claim 13 wherein the spacing between any two mutually overlapped rings is of such size as to provide open quarter wave 35 structures resonant at a predetermined frequency.
